UNITED STATES PATENT OFFICE.

HENRY A. STENGEL, OF DAYTON, OHIO.

MACHINE FOR GATHERING THE EDGES OF MATTRESSES FOR STITCHING.

No. 874,451.

Specification of Letters Patent.

Patented Dec. 24, 1907.

Application filed April 10, 1907. Serial No. 367,309.

To all whom it may concern:

Be it known that I, HENRY A. STENGEL, a citizen of the United States, residing at Dayton, in the county of Montgomery and State of Ohio, have invented certain new and useful Improvements in Machines for Gathering the Edges of Mattresses for Stitching; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention comprises a machine for gathering the edges of mattresses preparatory to stitching the same and contains the novel and desirable features hereinafter described and claimed.

Preceding a detailed description of the invention, reference is made to the accompanying drawings, of which—

Figure 1, is a front elevation of the machine showing the mechanism acting upon a mattress, a portion of which is broken away, and the mattress table and the supporting frame shown in section as partly broken away. Fig. 2, is an elevation of Fig. 1 looking from the left in Fig. 1. Fig. 3, is a detail view of one of the gathering fingers detached.

In a detail description of the invention, similar reference characters indicate corresponding parts.

The mattress table 5 is supported upon a suitable frame 2 with intervening rollers 25 journaled in brackets 27 on the lower side of said table, said rollers being flanged to run upon tracks 26 on said table frame. Secured to one side of the table frame 2 is a plate 1 providing bearings for certain parts to be specified. Extending perpendicularly from the plate 1 is an upright plate 3 which provides various bearings for the gearing and other parts as illustrated in the drawings. The upper portion of this plate 3 lies at right angles and is provided with an angular metallic plate 4 which incloses the upper edge of the mattress 6' as the said mattress is moved upon the table 5.

31 designates two gathering arms which have their inner ends 35 terminating at right angles and adapted to gather or embrace the opposite sides of the mattress at the edges. The gripping ends of said fingers

lie on the inner sides of the guide walls 4 and the outer ends of said fingers are pivoted to the upright plate 3 at 32.

28 designates two needles that enter openings 30 in the guide walls 4 and are made to penetrate the mattress at the edge to compress the excelsior or other filling 37, prior to the engaging of the mattress by the fingers 31. These needles 28 are swiveled to spur gears 10 and 12 at 29 and as said gears are opening the needles work in and out of the edge of the mattress from both sides, first, penetrating the mattress at the edge to compress the filling in the edge there- of immediately after which the fingers 31 engage the mattress and prepare it for stitching. The lower edge 36 of the mattress has been stitched and completed. It will be understood that only one edge of the mat- tress is operated upon at a time by the needles 28 and the gathering fingers 31.

The power is introduced to the machine through shaft 6 which carries a bevel gear 7 meshing with a bevel gear 8, the latter being on shaft 8' mounted in the plate 3 and upon which is also mounted a spur gear 9. The spur gear 9 drives the two gears 10 and 12 through which the needles 28 and the fingers 31 are operated; gear 12 being driven by an intermediate gear 11. The gears 10 and 12 carrying the needles rotate as indicated by the arrows in Fig. 1. Upon the shafts of gears 10 and 12, which shafts are also mounted in the plate 3, are cams 37 which engage in their rotation, the gathering fingers 31 and force them into the position shown in Fig. 1 where they are gathering the edge of the mattress; springs 34 fixed to the plate 3 at one end, engage the opposite sides of the fingers 31 and maintain said fingers in positions to be actuated at the proper time by the cams. The spur wheel 12 is trained to a spiral gear 17 through which the mat- tress table is operated through an interme- diate gear 13 which engages a lower gear 14, the shafts of both of said gears being mounted upon the plate 3. The shaft 15 of said lower gear 14 carries a worm wheel 16 which drives the spiral gear 17 before referred to, the lat- ter being on shaft 18 having bearings 19 on the plate 3 and in the side plate 1.

Upon the shaft 18 there is a spur wheel 20 which drives a smaller spur wheel 21 engag- ing a rack 39 on the lower side of the mattress table 5. The gear 21 is mounted upon an arm 22 loose upon shaft 18. By means of

this arm 22 the gear 21 may be released from engagement with the rack 39 when it is desired to stop the movement of the mattress table. Upon the free end of the arm 22 there is a screw 41 penetrating the same and passing through a slot 23 in the side plate 1, said screw being provided with a wing nut 24 by means of which it is tightened against the plate 1 at any point within the range of the slot 23. When the mattress is thus prepared for stitching, the work of stitching may be done by hand or by a machine; this operation has not been illustrated as it embodies no part of the present invention which comprises means solely for preparing the edge or edges of the mattress for stitching.

It will be understood that the needles 28 enter the opposite sides of the mattress in planes substantially at right angles to their positions as shown in Fig. 1, and from the positions shown in dotted lines across the lower gear 12. In the movements of said needles, their paths are substantially as shown by the curved dotted lines in the mattress filling. The said needles enter the mattress in straight lines, and as their supporting wheels 10 and 12 rotate, they are moved downwardly into the mattress filling, then upwardly and outwardly and in their upper and outward movements the filling of the mattress is pressed into the edge immediately after which the bent ends 35 of the fingers engage the mattress. In this sweeping movement of the needles, the guide flanges 4 serve as pivots for said needles.

As shown in the drawings, there is one set of needles comprising two needles which are pivoted to the gears 10 and 12. It will be understood that the inner ends of these needles describe substantially the same path of movement as do the outer ends. Each needle as it describes the circle of its movement, is caused to enter the edge of the mattress, and in its sweeping movement is caused to press up the filling in the corner and to withdraw at the completion of each rotation of its supporting gear, and to again make the circuit of its movement as the mattress is shifted for each stitch.

I claim:

1. In a machine of the type specified, devices adapted to penetrate the edge of a mattress to compress the portion of the mattress filling lying therein, gathering fingers adapted to gather the mattress edge after the filling

has been so compressed, means for actuating the compressing devices, and further means for actuating the gathering fingers after the compressing devices have penetrated the mattress.

2. In a machine of the type specified, needles adapted to penetrate opposite sides of the edge of a mattress to compress the mattress filling therein, gathering fingers adapted to engage opposite sides of the edge of a mattress to gather the edge in which the filling has been compressed, rotatable means upon which each of the needles are swiveled, cams for actuating the gathering fingers, and means for actuating said rotatable supports for the needles, and the cams for the gathering fingers.

3. In a machine of the type specified, a table adapted to support a mattress, inclosing guides for the edges of the mattress, piercing devices passing through openings in said inclosing guides and adapted to penetrate opposite sides of the edges of the mattress to compress the mattress filling therein, means for actuating said piercing devices to cause them to penetrate and withdraw from the mattress, gathering fingers penetrating openings in the inclosing guides and adapted to engage the opposite sides of the edges of the mattress after the piercing devices have been made to engage said edges, means for actuating said gathering fingers and said piercing devices from a common source of power, and means for actuating the mattress table from the same source of power.

4. In a machine of the type specified, a mattress table, means for actuating the same, an apertured guide inclosing the upper side edge of the mattress, needles penetrating openings in said guide and adapted to penetrate the portion of the mattress inclosed within the guide, means for actuating said needles to cause them to penetrate the mattress and withdraw therefrom, gathering fingers penetrating said guide and adapted to gather the edge of the mattress at a point lying inwardly from the point of penetration of the needles, and means for actuating said fingers to cause them to engage the edge of the mattress after the needles have penetrated the same.

In testimony whereof I affix my signature, in presence of two witnesses.

HENRY A. STENGEL
